UNITED STATES PATENT OFFICE.

EUGÈNE SCHNEIDER, OF LE CREUZOT, FRANCE.

GUN-MOUNTING.

1,120,247.

Specification of Letters Patent.

Patented Dec. 8, 1914.

Application filed March 26, 1914. Serial No. 827,465.

To all whom it may concern:

Be it known that I, EUGÈNE SCHNEIDER, of Le Creuzot, France, have invented a new and useful Improvement in or Relating to 5 Gun-Mountings, which is fully set forth in the following specification.

This invention relates to gun mountings that are employed on submersible or other vessels. Such mountings have been constructed and arranged in such a manner that the mounting and the gun as a whole can be lowered into a compartment provided for that purpose between the deck and the hull. These known arrangements have numerous 10 defects. For example the compartment formed between the deck and the hull cannot in practice be kept watertight and if it be desired to avoid any projections above the deck the said compartment can only be 15 of limited dimensions and only guns of small caliber and mountings of small height can be employed. The present invention 20 enables these defects to be remedied and also possesses other advantages hereinafter indicated.

My improved device enables the gun and the mounting as a whole to be caused to disappear completely inside the inner hull of the vessel in such a manner that when in 25 this position the gun mounting does not constitute an impediment to the crew. For this purpose the improved device comprises, according to my invention a guide system 30 for a tubular gun carriage support or carrier this guide being characterized by the fact that it is divided into fixed elements arranged in a hatchway of the submersible vessel, and into movable elements, arranged 35 in the hull and adapted to be brought, when desired, in line with the fixed elements or stowed away in a raised position toward the top of the hull. The fixed elements of the 40 guide support the gun carriage support when it is in the firing position. The movable elements when arranged in line beneath the fixed elements, enable the mounting and the gun to be lowered vertically into the interior of the vessel; they can then be raised together with the mounting into the stowed 45 away position which is horizontal or slightly inclined so as to render the interior of the vessel free from obstruction. Fixed 50 guide elements can also be arranged inside the hull in line with the movable elements 55 when the latter occupy the raised position.

In order that the said invention may be

clearly understood and readily carried into effect the same will now be described more fully with reference to the accompanying drawings in which:—

Figure 1 is a longitudinal sectional elevation showing in full lines the gun in the firing position, and in broken lines the gun in the position into which it is moved when about to be stowed away. Fig. 2 is a cross-sectional elevation of Fig. 1. Fig. 3 is a longitudinal sectional elevation showing in full lines the gun and the mounting in the stowed position and in broken lines the gun and its mounting in an intermediate position that is to say lowered vertically upon the fixed guides and upon the movable guides arranged in line beneath the latter. Fig. 4 is a sectional plan on the line A—A of Fig. 1. In Figs. 1 to 4 the fixed guides are shown as being arranged in a specially constructed hatch-way. Figs. 5 and 6 are views similar to Figs. 1 and 3 respectively showing the fixed guides in the usual hatch-way of a vessel.

The gun and mounting which may be of any known construction, in the example illustrated comprise a carriage *a* provided with a central pivot *b* carried in a bearing *c* formed in a tubular gun carriage support *d*.

In Figs. 1 to 4 a special hatchway *e* is provided, which constitutes a kind of cylindrical barrel opening at its lower end into the watertight hull *f* and at its upper end beneath the deck *g*. In this hatchway the fixed vertical elements *h* of a guide are provided for coöoperating with two longitudinal ribs *d'* projecting externally from the tubular gun carriage support *d*. At the lower extremity of the fixed guides or slideways *h*, movable guides or slideways *j* are hinged by means of hinges *i*; when desired the slideways *j* can be locked in the horizontal position indicated in full lines in Figs. 1 to 3, or brought into the vertical position in line beneath the fixed slideways *h*, as indicated by broken lines in Figs. 1 and 3. In this latter position each of the movable slideways can be locked to the corresponding fixed slideway by a detachable pin *k* carried by one of them and which engages in lugs *m*, *n* carried by the slideways *h* and *j* respectively, the holes in which then register. In the horizontal or raised position, the movable slideways *j* can be held by means of a hook *f'* pivoted beneath the hull *f* and engaging beneath a stay *j'* by

means of which the said slideways are connected. In the firing position (Figs. 1 and 2) the gun carriage support *d* is maintained upon the fixed slideway *h* by spring bolts *o*, 5 movable in a casing *p* fixed beneath the tube *d* and engaging in recesses *q* in the said slideways. These bolts can be drawn aside simultaneously by means of a lever *r* and connecting rods *s*. After the shoulder piece 10 *t* has been attached the gun is caused to assume the vertical position indicated by broken lines in Fig. 1. The operation of causing the gun and the mounting to move downward is then effected entirely from the 15 interior of the submersible vessel. A cable *u* operated by a winch can be attached by its free extremity to a lug *d*² on the support *d* this cable being carried over guide pulleys *v*, *w*. For operating the movable slideways 20 the same cable *u* can be passed over a guide pulley *x* carried by the hull and be attached to a lug *j*' projecting from one of the said slideways *j*. When the slideways *j* have been caused to assume the vertical position, 25 in line beneath the fixed slideway *h* they are locked by means of a pin *k*. The cable *u* is then detached from the lug *j*' and connected at *d*², after passing it over the pulleys *v* and *w*. The bolts *o* are released 30 by means of the lever *r* and the support and the gun are allowed to descend into the position indicated in broken lines in Fig. 3, the carriage support striking against the stay *j*³; at this moment the bolts *o* engage 35 automatically in the recesses *j*² formed at the lower part of the slideway *j*, thereby locking the carriage support upon the latter. The pin *k* is disengaged and the cable *u* is disengaged from *d*² and reengaged with 40 *j*'. By operating the winch in the proper direction the movable slideways *j* and the carriage support *d* locked thereon are raised and caused to occupy the position indicated in Fig. 3 in which it is secured by means 45 of the hook *f*.

In the example shown in Figs. 5 and 6 fixed slideways *y* are provided in line with the movable slideways *j* when the latter are

in the raised position. This renders it possible to bring the carriage support and the gun into position on the said prolongations *y* (Fig. 6) in order to free the hatch completely. The lower stay *j*³ which connects the movable slideways *j* is made circular in order to enable the carriage support to pass over the fixed extensions *y*, the movable slideways having been first of all locked by supporting bolts *z*. This modification possesses the advantage of not necessitating a special hatchway while at the same time leaving a free passage in the usual hatchway that is sufficient to enable the ammunition to be rapidly and conveniently supplied to the gun. The special hatchway and the usual hatchway can be closed by a cap or door of usual construction.

What I claim and desire to secure by Letters Patent of the United States is:—

A gun mounting of the kind set forth wherein there is provided a system of slideways or guides for the gun carriage support, comprising vertical elements fixed in a hatchway of the vessel, and movable elements adapted to be brought alternately in line with the fixed elements to form the lower part of the guide and to be raised into a horizontal or other appropriate position, in which, either alone or in conjunction with fixed extensions they serve as a support for the whole or a portion of the load, the fixed vertical guides being provided with means for engaging with the gun carriage support to hold it in the raised position and a fixed portion of the submersible vessel being provided with means for securing the movable guides in the raised position, substantially as and for the purpose specified.

In testimony whereof I have signed this specification in the presence of two subscribing witnesses.

EUGÈNE SCHNEIDER.
